UNITED STATES PATENT OFFICE

2,433,413

COMBINED RADIO TRANSMITTER AND LOUD-SPEAKER INSTALLATION

Cuthbert George Garland Withey, London, England, assignor to International Marine Radio Company Limited, London, England, a British company

Application February 8, 1945, Serial No. 576,838
In Great Britain February 21, 1944

2 Claims. (Cl. 179—2)

1

This invention consists in a combined radio transmitter and loudspeaker installation, more particularly though not exclusively for use aboard ship. Ships are usually fitted with radio apparatus and also frequently are provided with a loudspeaker installation. It is the object of this invention to effect economy in the apparatus provided for these separate purposes.

According to the present invention we provide the combination with a radio transmitter installation of a loudspeaker installation, a microphone additional to that of the radio transmitter installation, a switch to connect the said microphone to the input of the radio transmitter and a second switch adapted to connect the output of a low frequency amplifier in said radio transmitter installation either to the radio frequency stages of said last mentioned installation or to the loudspeaker installation.

The invention will be better understood from the following description taken in conjunction with the accompanying drawings in which:

Fig. 1 is a typical circuit diagram of an installation according to the invention in a case in which the radio transmitter uses plate circuit modulation of suitable power to load the loudspeaker.

Fig. 2 is a schematic diagram of an installation according to the invention in a case in which the radio transmitter uses grid circuit modulation of insufficient power fully to load the loudspeaker.

Referring to the drawings, Fig. 1 is a circuit diagram of an installation comprising a radio transmitter installation of a well known kind combined with a loudspeaker installation in accordance with this invention. The output from a high frequency oscillator O is connected by means of a transformer T3 in push pull to the grids of two valves V1 and V2, the anodes of which valves are in parallel and are connected to the high tension supply through a tuned circuit and the secondary of an audio frequency transformer T2. The microphone, key buzzer audio oscillator or other sources of signals is connected to the points M1, M2 and thus to the primary of a transformer T1, the secondary of which is connected to the input of a push pull audio frequency amplifier V3, V4, the output of which is connected to the primary of transformer T2. The inductance of the tuned high frequency output circuit serves as the primary of transformer T4 the secondary of which is included in the antenna circuit. According to the invention a switch S1 is provided, which in one position connects the secondary of transformer T2 in its normal position in the an-

2

ode circuit of valves V1 and V2 so that the high frequency is modulated from the signal source and in another position connects the secondary of transformer T2 to a directional loudspeaker LS. The latter may include an impedance matching transformer if necessary.

It will be noted that the connections made by the switch S1 are such that when the audio frequency amplifier V3, V4 is connected to the loudspeaker LS the high tension supply is disconnected from the valves V1 and V2 and the oscillator O so that the H. F. portion of the installation is rendered nonradiating, but remains connected to the valves V3 and V4.

15 Since it is usually required that the directions or information given over the loudspeaker LS should originate from the bridge, a microphone K with a push button S2 switch in series therewith is situated on the bridge and connected to the wires M3 in shunt to the normal microphone etc. of the radio transmitter.

In Fig. 1 anode modulation is used and the modulation in the radio transmitter takes place at a high power stage. In such circuits the audio frequency amplifier V3, V4 is usually of sufficiently high power to develop a volume of sound in a directional loudspeaker LS adequate for hauling over the maximum distances at present used for such purpose.

20 Fig. 2 is one example of the application of the invention to an installation in which the radio transmitter uses grid circuit modulation and the audio frequency output is low (below 10 watts). The input to a high frequency amplifier HFA includes in series secondaries of high and audio frequency transformers by means of which the outputs of a high frequency oscillator O and an audio frequency amplifier LFA1 are impressed thereon.

25 The signal source is connected to points M1, M2 in the input of amplifier LFA1. In applying the present invention, a switch S1 is provided and in one position completes the connection between the secondaries of the high and audio frequency transformers in the input of amplifier HFA and in the other position connects the secondary of the audio frequency transformer to the input of a second audio frequency amplifier LFA2 the output of which is connected to a directional loudspeaker LS. The second audio frequency amplifier LFA2 is necessary because in the case of a low power radio transmitter such as is illustrated, the low frequency amplifier LFA1 does not usually develop sufficient power for hauling over the maximum distances for which a directional loud-

speaker is at present used. Even in this case, however, considerable economy in components over separate radio transmitter and loudspeaker installations is effected. In the same way as described with reference to Fig. 1 a microphone with a push button switch located in the bridge is connected across the points M₁, M₂ in shunt to the normal microphone of the radio transmitter installation.

The loudspeakers may be used for aural communication (alternative to radio) between ships in convoy, between the bridge or other control centre of a ship and remote sections of the same ship, between a ship and a lighthouse or other point on shore, e. g., for docking instructions or the like, or it may be used between a ship and lifeboats or other rescue services.

The installation of a loudspeaker system to utilise part of the equipment of the audio transmitter possesses considerable advantages over a separately installed loudspeaker system in that separate microphones, amplifiers, batteries, or generators are not in general required; conversion of any ship fitted with a radio transmitter is easy; the changeover from radio to loudspeaker communication can be instantaneous, e. g., as distance increases and aural communication fails via the loudspeaker channel, contact can almost instantly be made by radio, whilst the possibility of using Morse communication via the loudspeaker allows greater range to be obtained by direct aural transmission.

What is claimed is:

1. In a communication system for a ship where it is desirable to communicate with another ship by a loudspeaker or by radio using either voice or code signals, the combination of, a radio transmitter having a radio-frequency circuit portion and an audio-frequency circuit portion, a microphone connected to the input of the audio-frequency circuit portion, means to introduce code signals to the input of the audio-frequency circuit portion, a loudspeaker operable when connected to the output of the audio-frequency circuit portion to reproduce the voice or code signals for acoustic transmission to another ship, and a switching assembly adapted to connect the output of the audio-frequency circuit portion selectively to the loudspeaker or to the radio-frequency cir-

cuit portion whereby the voice or code signals are transmitted by the loudspeaker acoustically or by the radio transmitter, said switching assembly including a switch unit which is closed by the connecting of the audio-frequency circuit portion to the radio-frequency circuit portion and which switch unit when closed connects a source of power to energize the radio-frequency circuit portion.

2. In a communication system for a ship where it is desirable to communicate with another ship by a loudspeaker or by radio using either voice or code signals, the combination of, a radio transmitter having a radio-frequency circuit portion of the plate-circuit modulation type and an audio-frequency circuit portion which includes an audio-frequency transformer, a microphone connected to the input of the audio-frequency circuit portion, means through which code signals may be introduced to the input of the audio-frequency circuit portion, a loudspeaker operable when connected to the output of the audio-frequency circuit portion to reproduce the voice or code signals for acoustic transmission to another ship, and a switching assembly adapted to connect the secondary winding of the audio-frequency transformer selectively to said loudspeaker or in series with the plate circuit of said radio-frequency circuit portion whereby the voice or code signals are transmitted by the loudspeaker or by the radio transmitter, said switching assembly including a switch unit which is closed by the connecting of the audio-frequency circuit portion to the radio-frequency circuit portion and which switch unit when closed connects a source of power to energize said radio-frequency circuit portion through the secondary winding of said audio-frequency transformer.
